UNITED STATES PATENT OFFICE.

WILLIAM W. PRETTS, OF PLATTEVILLE, WISCONSIN.

VAGINAL SPECULUM AND RETRCTOR.

1,194,319.

Specification of Letters Patent.

Patented Aug. 8, 1916.

Application filed February 23, 1915. Serial No. 9,983.

To all whom it may concern:

Be it known that I, WILLIAM W. PRETTS, a citizen of the United States, residing at Platteville, county of Grant, and State of 5 Wisconsin, have invented certain new and useful Improvements in Vaginal Specula and Retractors, of which the following is a specification.

My invention relates to surgical apparatus, and particularly to an improved 10 speculum and retractor.

The primary object of my invention is to provide a device of the character mentioned by means of which the walls of the vagina 15 and the cervix uteri (neck of the womb) may be rendered readily accessible for diagnosis or treatment; and which shall be particularly adapted for use in surgical operations upon the parts mentioned and on 20 the perineum.

A further object of my invention is to provide a device as mentioned, which shall properly hold the parts to be treated or operated upon, and at the same time shall be 25 practically out of the field of operation.

A further object is to provide a device of the class under consideration which shall be self-retaining.

A further object is to provide a device as 30 mentioned which may be used with the handles turned in any direction, whereby it is adapted for use with the patient in any position.

A further object is to provide a retractor 35 of the class mentioned by means of which the vagina may be retracted to its full extent without causing injury to the urethra.

A further object is to provide a device of the class mentioned which may be readily 40 taken apart for cleaning and sterilizing.

Other objects will appear hereinafter.

With these objects in view, my invention consists generally in a pair of pivotally connected members provided at one end with 45 handles and at the other end with blades extending at substantially right angles thereto and substantially parallel to each other, and a third blade slidably connected to the first mentioned members and adapted to be moved toward or away from the first mentioned blades on a medial line, said third blade being shaped to assist in retaining the device in the vagina.

My invention further consists in the 50 pivotally connected members equipped with the blades as mentioned, further character-

ized by having the portion of the members between the pivot and the blades curved outwardly away from each other and arched outwardly in the opposite direction from the 60 blades, to give a clear field of operation.

My invention consists further in providing a device as mentioned in which the third blade is formed with a slot to prevent pressure and consequent injury to the urethra. 65

My invention further consists in a device as mentioned wherein the pivoted members and the slideable blade are connected by the same separable device.

My invention further consists in improved 70 means for holding the device in expanded position, and in various details of construction and arrangements of parts all as will be fully described hereinafter and particularly pointed out in the claims. 75

My invention will be more readily understood by reference to the accompanying drawings forming a part of this specification and in which,

Figure 1 is a plan view of a vaginal speculum and retractor embodying my invention, illustrating the same in contracted position, Fig. 2 is a side elevation of the same, Fig. 3 is a plan view in expanded position, Fig. 4 is a detail view of the third or auxiliary blade, Fig. 5 is a section on the line 5—5 of Fig. 3, Fig. 6 is a section on the line 6—6 of the same figure, Fig. 7 is a section on the line 7—7 of Fig. 2, and Fig. 8 is a detail view of the pivotal connection of the 80 main members. 85

Referring now to the drawings, 10—10 indicate a pair of pivotally connected members, each comprising a handle portion 11 and a curved arm portion 12 angularly disposed with relation to the handle portion, said portions merging into each other at substantially the point of pivotal connection of the members 10. The handle portions 11 are preferably straight and terminate in rings 13 for the reception of the thumb and finger used in operating the device. 90 95

The arms 12, adjacent the handles, extend abruptly outwardly at a considerable angle thereto, and then curve inwardly, terminating in blades 14 at substantially right angles to the general plane of the members 10. These arms are also arched outwardly away from said plane and in the opposite direction from the blades. By this arrangement 100 105 the blade supporting arms are maintained 110

in such position as not to interfere with the field of operation. The blades 14 are substantially straight from end to end, are slightly convex on the outer face and have well rounded edges and corners to prevent injury to the parts or undue pain to the patient.

At the juncture of the arm and handle portions, 11 and 12, the members 10 are provided with means for pivotally connecting the same. To this end one of the said members is provided with a pair of ears 15, the outer faces of which are in the planes of the outer faces of the member; and the other member is provided with a single ear 16 fitting snugly between the ears 15. The ears 15 and 16 are semi-circular and the adjacent walls of the opposite members are correspondingly recessed to snugly receive the same. The said ears are provided with aligned perforations 17 to receive a pivot bolt 18, the latter being equipped with a binding thumb nut 19. A washer 20 is interposed between the nut 19 and the adjacent ear 15.

21 indicates the third or auxiliary blade which is provided with a shank 22 at substantially right angles thereto, and parallel with the members 10. The shank 22 is provided with a longitudinally disposed slot 23 to receive the bolt 18, and when the third blade is used the shank 22 is arranged between the washer 20 and the thumbnut 19. The blade 21 is therefor adapted to be moved toward or away from the blades 14 on a medial line, and is held in position by the same device that connects the pivoted members 10. The end of the shank 22 is provided with a hook or finger hold 24 by means of which the blade 21 is moved and this is arranged adjacent the rings 13 so that the device may be manipulated with one hand.

The blade 21 is convex in cross section on its outer face, for the reasons explained in relation to the blades 14, and is furthermore convex longitudinally, adjacent the free end so as to assist in retaining the device within the vagina, as will be readily understood. Adjacent its base the blade 21 is provided with a longitudinally disposed slot or recess 25 to prevent the blade from pressing the urethra against the pubic arch with consequent injury to the former, when said blade is used in such position as would otherwise press thereon.

Means must be provided for holding the

device in operative position, that is with the blades 14 separated. To this end I provide a threaded bar 26, pivotally connected to one of the handle portions 13 and engaging between lugs on the other handle portion, and provide means for locking the bar in position. The bar is preferably flat, as illustrated in the drawings and is formed with shallow grooves 27 in its opposite faces. The bar is pivoted at one end between ears 28 on the extreme outer portion of one of the rings 13 and is adapted to be swung into position between ears 29 on the opposite ring. A thumb nut 30 is threaded on the bar 26 to engage the outer edges of the lugs 29 which are flattened to form a seat for the same. A thumb screw 37 is threaded through one of the lugs and engages in one of the grooves 27. This holds the bar in position between the ears 29 and at the same time permits longitudinal movement thereof. A slight turn of the screw releases the bar so that it may be thrown from between the lugs to permit quickly contracting the device.

I claim:—

1. In a device of the class described, a pair of pivotally connected members, handles upon one end of said members, blades upon the opposite ends of said members, a bar pivotally connected to one of said handles and provided with a longitudinally disposed slot, a pair of lugs upon the opposite handle to receive said bar between them, and a thumb screw threaded through one of said lugs and adapted to engage in said slot, substantially as described.

2. In a device of the class described, a pair of pivotally connected members, handles upon one end of said members, blades upon the opposite ends of said members, a bar pivotally connected to one of said handles and provided with a longitudinally disposed slot, a pair of lugs upon the opposite handle to receive said bar between them, a thumb screw threaded through one of said lugs and adapted to engage in said slot, and a thumb nut threaded upon said bar and adapted to engage said lugs, substantially as described.

In testimony whereof I have signed my name to this specification in the presence of two subscribing witnesses.

WILLIAM W. PRETTS.
